UNITARY CONTROL FOR WASHING MACHINES

Walter W. Hoyle and Stuart G. Mundt, Syracuse,
N. Y., assignors to Easy Washing Machine Cor-
poration, Syracuse, N. Y., a corporation of
Delaware

Application November 25, 1953, Serial No. 27,795

Term of patent 14 years

(Cl. D49—1)

To all whom it may concern:

Be it known that we, Walter W. Hoyle and Stuart G. Mundt, citizens of the United States of America, residing at Syracuse, in the county of Onondaga and State of New York, have invented a new, original, and ornamental Design for a Unitary Control for Washing Machines, of which the following is a specification, reference being had to the accompanying drawings, forming part thereof, in which:

Figure 1 is a plan view of the unitary control for washing machines, showing our new design; and

Figure 2 is a sectional view thereof taken substantially on the line 2—2 of Figure 1.

We claim:

The ornamental design for a unitary control for washing machines, substantially as shown.
